E. Lester,

Casting Trundle-Heads for Axletrees,

Patented Feb. 12, 1807.

~~Obenzer & Postle~~
Postle's Patent

The Schedule referred to in the above Letters Patent and making part of the same, containing a description in the words of the said Obenzer & Postle, himself, of his method of making moulds for casting iron hub heads of any kind, & indeed for the axles of wheels and of wheel carriages, of every size & description.

Take two pieces of seasoned plank of (say) an inch and a half thickness, each - cut them equally round and each of a diameter (say) three inches, and joint them so that they will come close together. Then draw another circle on one side of each piece of the diameter of (say) two inches, then bore with a fore-axle (Rif. Ray) nine or twelve three quarter six inch holes in each piece, outside of the circles, at equal distances from each other, to the depth of (say) one inch, and a quarter the inner edge of each hole coming to the circular line, and the outer circumference of the holes will extend a quarter of an inch beyond the circumference of each of the two pieces. The pieces are then to be put together and round rollers are put into each of the holes bored in manner aforesaid which are to be so loose as to be turned round with ease (The rollers however are to be cast by themselves) There are an eight sided hole through the centre of the two pieces of the diameter of (say) one inch and a half and the making of the moulds are then completed. The iron hub when cast is fastened firmly upon the axle, so as to come in contact with, and exactly fit the two iron boxes, which are usually placed in each end of the hub, of the wheel of the carriage. The axle is ought to be of iron; it may however be of wood. The advantage contemplated to be derived from the above plan is, that the wheel will turn much easier upon the axle, by means of casting upon the rollers, which turn as the wheel turns, as the friction will not be half so great as in the common method now in use, it is also expected that the iron axle (whatever may be) which may be applied to the rollers to make them turn easier, will not exhaust, wear & tear quickly as that which is applied to the axle of a wheel in the usual manner, at the same time the axle will be saved from

wearing and the expense of "skins" in leather bushes. It is expected that the undersized bottoms will account for the fact, on account of their being the greatest weight, but this may be remedied by occasionally changing them, by unloosing the trundle head from the axle tree, then placing those which were under, up foremost, yet and when all the collars . . . . . become worn out, new ones can be put in. There ought to be a narrow groove in each of the trundle heads, ^{which should be deep enough to hold the axle hub, so that the wheel may turn freely} to hold the hub of the axle, & neatly. very little dirt would work in. The trundle heads ought to be a little longer than the bases of the hubs, as it is usual to leave the axle room enough to play off and on upon the axle tree as much as half an inch or more. The above dimensions of the trundle heads, are given merely for (original design) They may be (original estimate) diminished &c. as will be found most convenient.
